CHILD'S BREAKFAST SET

William N. Dresden, Chicago, Ill.

Application July 9, 1954, Serial No. 31,353

Term of patent 7 years

(Cl. D44—15)

Fig. 1.

Fig. 2.

Fig. 3.

To all whom it may concern:

Be it known that I, William N. Dresden, a citizen of the United States, and a resident of Chicago, in the county of Cook and State of Illinois, have invented a new, original, and ornamental Design for a Child's Breakfast Set, of which the following is a specification, reference being had to the accompanying drawing, forming a part thereof, and in which:

Fig. 1 is a front elevational view of a child's breakfast set in stacked position, showing my new design;

Fig. 2 is rear elevational view of the same;

Fig. 3 is a perspective view of the breakfast set showing the pieces thereof in separated position.

I claim:

The ornamental design for a child's breakfast set, as shown.
